UNITED STATES PATENT OFFICE.

JOSEPH T. RADEMAKER AND BERNARD F. RADEMAKER, OF CLEVELAND, OHIO.

FOLDING-CRIB ATTACHMENT FOR BEDS.

No. 902,684.

Specification of Letters Patent.

Patented Nov. 3, 1908.

Application filed May 31, 1907. Serial No. 376,669.

To all whom it may concern:

Be it known that we, JOSEPH T. RADEMAKER and BERNARD F. RADEMAKER, citizens of the United States, residing at Cleveland, in the county of Cuyahoga and State of Ohio, have invented a new and useful Improvement in Folding-Crib Attachments for Beds, of which the following is a specification.

10 This invention relates generally to folding cribs, and more particularly to a folding crib adapted to be attached to a bedstead and another object is to construct said attachment in such a manner that it can be 15 folded when not in use and pushed beneath the bed so that it will not occupy any room space when not in use.

Another object is to provide an attachment of this kind which can be used in connection with any of the well known constructions of bedsteads.

With these various objects in view the invention consists in the novel features of construction, combination and arrangement all 25 of which will be fully described hereinafter and pointed out in the claims.

In the drawings forming a part of this specification:—Figure 1 is a perspective view of a bedstead having our improved 30 folding crib attached thereto, the crib being opened out ready to receive the mattress. Fig. 2 is a perspective view showing the crib folded and pushed beneath the bedstead, the mattress of the bed and crib being omitted 35 for clearness of illustration. Fig. 3 is a sectional elevation, Fig. 4 is a detail sectional view taken through one of the supports.

Referring to the drawings, A indicates an ordinary metal bedstead, to the side rails of 40 which are attached the adjustable hanger brackets B and connected to these hanger brackets are the supporting guides C, there being two such guides, each supported by the adjustable brackets at each end and it will 45 be noted that these supporting guides are arranged adjacent the head and foot of the bedstead and it will of course be understood that they can be attached at any convenient point. Sliding in these supporting guides 50 are the rods or bars D connected at their outer ends by the side bar D', and adjacent their inner ends by means of the bar D'', said rods and bars constituting a frame which is adapted to slide back and forth in 55 the supporting guides beneath the bedstead proper. Each sliding bar D, carries two

depending hangers E and pivotally connected to each hanger is a link arm F, the upper end of each link arm being pivotally connected at F' to the ends G of a rectangular shaped mattress supporting frame, said frame being of a size slightly smaller than the space inclosed by the bars D, D' and D''. This frame G is intended to hold the mattress of the crib. The side H, of the crib 60 is pivotally connected to the side bar of the sliding frame and is adapted to fold inwardly and downwardly upon the mattress carrying frame and as the said side folds downwardly the mattress carrying frame 70 drops and thereby lowers the said mattress to such a point that when the crib has been folded the crib with the mattress and bed clothes can be pushed under the bedstead. In order to accomplish these movements we construct 75 the side H of the upper bar H', lower bar H'' and connecting rods H''. The rod H'' has depending legs H⁴, which are pivotally connected at H⁵ to the bar D'' and this lower bar H'', is provided with an arm H⁶ adjacent each end, which arm is pivotally connected to a link arm F² which is also pivotally connected to the mattress frame at F' where the outer link arm F is pivoted, and by reference to Fig. 3 it will be seen that 80 when the side H is folded inwardly and downwardly the mattress frame will be lowered as shown in dotted lines.

The ends I, consist of the upper bar I' and lower bar I'' and connecting rod I³ and the lower bars I'' are hinged at I⁴ to the side bars D of the sliding frame. K indicates the legs which are connected to the outer ends of the ends I, and are provided at their upper ends with half sockets K' into which fit the ends of the upper rod H' and a suitable sleeve sliding on said bar can be used to securely lock the folding sides and ends in their proper position. As before stated the side H, is first folded causing the mattress frame to drop and then the ends are folded over and after the side and ends are so folded the entire folded crib together with the mattress and bed clothes can be pushed under the bedstead. It will thus be 95 seen that we provide a simple and efficient folding crib attachment capable of carrying out all of the objects heretofore referred to.

Having thus fully described our invention, what we claim as new and desire to secure 100 by Letters Patent, is:—

1. The combination with a bedstead, of

- the hangers connected thereto, the supporting guides connected to said hangers a sliding frame working in said guides, the mattress frame movably supported upon the 5 sliding frame, pivoted side and ends and means for holding said side and ends in their open positions together with means for raising and lowering the mattress frame simultaneously with the side.
- 10 2. In a device of the kind described the combination with the supporting guides, of the sliding frame, the depending hangers connected to the said frame, the mattress frame and the link arm connecting said 5 frame to the depending hangers, the hinged side and ends and the link arm connecting the side and mattress frame whereby as the side is raised and lowered the mattress frame will also be raised and lowered.
- 15 3. The combination with a bedstead, of the adjustable supporting guides suspended

therefrom, the frame sliding in said guides, a mattress frame, and link connection between the sliding and mattress frames, the ends hinged to the frame, the side hinged 25 also to the frame and connected with the mattress, for the purpose specified.

4. The combination with a bedstead, of the suspended guides connected therewith, the frame, sliding in said guides, ends of 30 the crib pivoted to said frame, each end having a supporting leg, a side hinged to the frame, means for locking the side and ends together, and a mattress frame, connected with the sliding frame, and movable with 35 reference thereto, together with means for moving the same as specified.

JOSEPH T. RADEMAKER.
